UNITED STATES PATENT OFFICE.

SOREN HANSSON, OF NEW GLASGOW, NOVA SCOTIA, CANADA.

TRUCK-FRAME.

1,233,349.

Specification of Letters Patent. Patented July 17, 1917.

Application filed October 18, 1916. Serial No. 126,339.

To all whom it may concern:

Be it known that I, SOREN HANSSON, a resident of New Glasgow, in the Province of Nova Scotia and Dominion of Canada, have invented a new and useful Improvement in Truck-Frames, of which the following is a specification.

The invention relates to side frames for trucks and methods of making the same. It is particularly applicable to side frames for vehicle trucks such as the trucks of railway cars.

The side frames of car trucks are generally constructed so as to rest at their ends on journal boxes and support from a depending portion at their center a bolster upon which the body of the car rests. These frames must necessarily have great strength and at the same time they should be as small and light as possible so as to occupy little space and not unduly increase the weight of the truck. The frames must be constructed within certain limits as to width because the lower edge of the depending portion must be a certain distance above the surface of the truck upon which the car is to run and the upper portion of the side frame must not be too high in order not to require the car body to be mounted too high.

When the frames are made of cast metal they are heavy, clumsy, and subject to breakage by shock. When they are fabricated out of various metal shapes which are riveted or otherwise fastened together, they are relatively expensive and subject to all the defects of such built-up structures. The present invention relates to an improved method of making side frames from a single piece of rolled plate metal, said frame having all the advantages of a cast frame with increased strength, especially as to tensile strains and resistance to shock which inheres in the character of the metal used. By this improved process a neat, relatively light and strong side frame may be inexpensively produced.

One of the objects of the invention is to provide an improved side frame for trucks and a process of making the same.

Another object is to provide an improved integral side frame produced from a single sheet of rolled metal plate.

Other objects and advantages will be hereinafter described.

The accompanying drawings illustrate

embodiments of the invention. The views of the drawings are as follows:

Figure 1 is a plan view of a sheet metal plate showing in dotted lines the manner in which the side frames are cut out of it.

Fig. 2 is a plan view of the stamping as cut from the plate.

Fig. 3 is an end view of the frame shown in Fig. 2.

Fig. 4 is a plan view of the stamping after it has been subjected to certain forging operations.

Fig. 5 is a cross section on the line 5—5 of Fig. 4.

Fig. 6 is a cross section on the line 6—6 of Fig. 4.

Fig. 7 is a cross section on the line 7—7 of Fig. 4.

Fig. 8 is a cross section on the line 8—8 of Fig. 4.

Fig. 9 is a side elevation of the central portion of the side frame showing the spring plank of the truck frame in position.

Fig. 10 is a cross section on the line 10—10 of Fig. 9.

Fig. 11 is a side elevation of a modified form of the truck frame.

Fig. 12 is a top plan view thereof.

Fig. 13 is a cross section on the line 13—13 of Fig. 11.

Fig. 14 is a side elevation of the central portion of a form of the truck frame similar to that disclosed in Fig. 4 but having a different shape given to the forged portions thereof.

Fig. 15 is a cross section on the line 15—15 of Fig. 14.

Fig. 16 is a sectional view of an alternative shape that may be given to the forged portions of a frame such as shown in Fig. 14.

The side frame is cut from a blank of rolled plate metal by means of a suitable stamping or cutting machine in the manner illustrated in Fig. 1 and to the shape illustrated therein. This method of cutting the blank from a sheet metal plate is efficient and economical since it reduces the amount of waste metal to a minimum. The metal from the openings in the blank may be used for making other and smaller accessories for cars and car trucks.

The side frame as stamped from the metal strip is of the shape shown in Fig. 2 and comprises what is known in the art as a pedestal frame. It is provided with a

bolster opening 1 for receiving a bolster for supporting the car body, and recesses 2 and 3 forming pedestal jaws 4, 5 and 6, 7, which fit over the journals supported by the axles 5 of the car wheels. The upper portion of the frame 8, 9, 10, constitutes what is known as the upper chord, and the lower portion 11, 12, 13, constitutes the lower chord. The frame also has openings 14 and 15 stamped therein, 10 the metal being cut out to form these openings because it is not needed at these points. The vertical portions 16 and 17 constitute what are known as the columns of the truck. The frame is stamped from a metal strip 15 of uniform thickness, preferably a strip about two inches thick. This thickness of metal produces a frame in which substantially all the parts have sufficient strength for the purpose required.

20 As previously pointed out, however, the total width of the frame must be within certain limits. This requires that the portions of the frame above and below the bolster opening be relatively narrow. If 25 they are made too narrow, they will in some cases not possess the required strength. If, in order to give them the necessary strength, the thickness of metal used to make the truck is increased, the other portions of the 30 frame will have excess strength, and the weight and cost of the frame will be unduly increased. In order to avoid this difficulty the portions of the side frame 9 and 12 above and below the bolster opening are made 35 wider than desirable for the finished frame and they are then subjected to a forging operation to decrease their width and increase their thickness without decreasing their strength. The excess width of metal is preferably provided in the bolster opening so 40 that the opening in the frame as it is cut from a blank is smaller than that required in a finished frame.

The portions of the frame above the recesses 2 and 3 may also be made wider than necessary and later reduced in width and increased in thickness, as will be hereinafter described. The recesses are not made as deep 45 in the stamped-out blank as they are in a finished side frame.

50 After the frame is cut to the shape shown in Fig. 2, it is subjected to a forging operation in which the metal above and below the bolster opening is forged to increase its thickness at certain points and reduce its width. If the bolster opening has been made 55 smaller than desired it is enlarged to the proper size during the forging process. The shape of the sections 9 and 12 above and below the opening is shown in cross section in Fig. 5.

60 This forging operation reduces the width of the portions 9 and 12 so that the total width of the truck is within the proper limits. At the same time the strength of

the sections 9 and 12 is maintained at the proper value for lateral stress.

In case it is desired to strengthen the metal above the recesses 2 and 3 and adjacent the pedestal jaws the metal at the points 70 18 and 19 is also forged to increase its thickness, preferably to a shape such as shown in section in Fig. 8.

75 During or after the forging operation the edges of the frame are beveled, as shown in Fig. 4. This gives the frame a neat appearance and destroys rough edges which would give the frame an unfinished appearance and be detrimental in handling the same. The manner in which the edges are beveled is clearly illustrated by the cross section views of Figs. 6 and 7 which illustrate the cross section of the portion 8 of the upper chord and the portion 11 of the lower chord.

80 By the process above outlined a side frame may be cut from a sheet of rolled plate metal with minimum waste of material. The forging process serves to strengthen the portions subjected to the greatest shock and at the same time give them the requisite width that is necessary in a practical frame of this type. The manufacturing process is simple, relatively inexpensive and produces a neat, rigid frame having the required strength 85 with a minimum weight. The inherent properties of rolled sheet metal enable the frame to withstand tensile strains and shocks much better than the frames which are cast or built out of various iron shapes.

90 The metal above and below the bolster opening and above the journal recesses may be otherwise shaped than as shown in cross section in Fig. 5. For example, Figs. 14 and 15 illustrate a modification in which the metal is otherwise shaped. Fig. 16 illustrates a modification in which the forged portions are given a channel shape. It is also within the scope of the invention to shape the portions above and below the bolster opening differently, or the portions 95 of the frame adjacent the pedestal jaws may be shaped differently than the portions adjacent the bolster opening. It is also to be understood that other portions of the frame 100 can be forged to thicken them if desired.

105 The manner in which the spring plank for supporting the bolster is attached to a frame of this character is shown in Figs. 9 and 10. The plank 20 comprises a channel beam 110 having riveted to one of its ends a cast or forged bracket 21 having projections 22 and 23 which extend down on opposite sides of the portion 12 of the lower end. These projections prevent endwise movement of the 115 plank, and lateral movement thereof is prevented by the edges of the bolster opening. One of these brackets 21 is riveted or otherwise secured to each end of the plank 20, as will be readily understood. With this con- 120

struction the bolster plank may be easily removed and the truck taken apart without unfastening any bolts or rivets by merely taking out the bolster and lifting out the 5 spring plank.

A further modification is illustrated in Figs. 11, 12 and 13. In this form the portions of the frame above and below the bolster opening are forged into the shape of an 10 I-beam, as illustrated in Fig. 13. Also, in this form, substantially the entire upper chord of the frame is forged, as will be clear from an inspection of Fig. 11. The forging below the bolster opening also extends 15 on both sides thereof. The I-beam shape gives a maximum strength for a minimum width, as will be readily understood. If desired, the forging may be extended farther or not as far as in the modification of 20 Fig. 11. In each case, wherever it is desired to forge a portion of the frame, that portion is cut out in the blank of greater width than it is desired in the finished frame. The portion is then forged to reduce the width 25 and increase its thickness by shaping it in any one of the several shapes shown or in any other desirable shape.

It is to be understood that the structure shown is for purposes of illustration only 30 and that other structures may be devised which come within the spirit and scope of the appended claims.

What is claimed is:—

1. The method of making a vehicle truck 35 side frame which comprises stamping said frame out of a single sheet of metal of uniform thickness to thereby produce a frame of uniform thickness, and forging certain portions of the stamping to decrease the 40 width and increase the thickness of said portions.

2. The method of making a vehicle truck 45 side frame which comprises stamping said frame out of a single sheet of metal of uniform thickness with certain portions of the stamping of excess width, and forging said portions to reduce their width and shape them to give the required strength.

3. The method of making a vehicle truck 50 side frame which comprises stamping said frame out of a single sheet of metal of uniform thickness with certain portions of the stamping of excess width, and forging said portions to reduce their width and increase 55 their thickness.

4. The method of making a vehicle truck 60 side frame which comprises stamping said frame out of a single sheet of metal of uniform thickness to form a frame of uniform thickness with a bolster opening therein, and forging the metal above and below the bolster opening to decrease its width and increase its thickness.

5. The method of making a vehicle truck 65 side frame, which comprises stamping said

frame out of a single sheet of metal with a bolster opening therein, the metal above and below said opening being of excess width, and forging the metal above and below the bolster opening to decrease its width 70 and shape it to provide the proper strength for the required width.

6. The method of making a vehicle truck side frame, which comprises stamping said frame out of a single sheet of metal with a bolster opening of reduced size, and forging the metal adjacent the bolster opening 75 to produce an opening of the required size and to shape the metal to give it the required strength.

7. The method of making a vehicle truck side frame which comprises stamping said frame out of a single sheet of metal of uniform thickness to produce a frame of uniform thickness with a bolster opening therein and pedestal jaws near its ends, and forging the metal adjacent the bolster opening 85 and the pedestal jaws to decrease its width and shape it to provide the proper strength.

8. The method of making a vehicle truck side frame, which comprises stamping said frame out of a single sheet of metal with a bolster opening therein and pedestal jaws near its ends, and forging the metal adjacent the bolster opening and the pedestal 95 jaws to thicken the metal to give it the proper strength for a required width.

9. The method of making a vehicle truck side frame, which comprises stamping said frame out of a single sheet of metal with a 100 bolster opening therein and recesses near its ends, the metal adjacent the bolster opening and the recesses being of excess width, and forging the metal adjacent the opening and the recesses to reduce its width and 105 shape it to give the proper strength for the required width.

10. The method of making a vehicle truck side frame, which comprises stamping said frame out of a single sheet of metal with a 110 bolster opening and recesses for the truck journals of reduced size, and forging the metal adjacent the bolster opening and the recesses to thicken the metal and produce openings of the required size.

11. An integral side frame for vehicle trucks cut from a single piece of plate metal and being of uniform thickness throughout except for certain portions which are forged to increase their thickness to provide increased strength for a required width.

12. An integral side frame for vehicle trucks cut from a single piece of metal and being of uniform thickness throughout except for certain portions thereof which are forged to decrease their width and increase their thickness to provide the proper strength for the required width.

13. An integral frame for vehicle trucks cut from a single piece of plate metal of 130

uniform thickness and having a bolster opening therein, the portions of said frame above and below said opening being forged to increased thickness.

14. An integral side frame for vehicle trucks cut from a single piece of plate metal of uniform thickness and having a bolster opening therein, the portions of said frame above and below said opening being forged to reduce their width and shaped so that their strength is not decreased.

15. An integral side frame for vehicle trucks cut from a single piece of plate metal of uniform thickness and having a bolster opening therein and pedestal jaws adjacent its ends, the portions of said frame adjacent the bolster opening and the jaws being forged to decrease their width.

16. A vehicle truck side frame comprising a single piece of metal cut to shape with a bolster opening near the center thereof and recesses at its ends, the metal adjacent the bolster opening and the recesses being forged to increase its thickness.

17. A vehicle truck side frame comprising a single piece of metal cut to shape with a

bolster opening near the center thereof and pedestal jaws near its ends, the metal adjacent the bolster opening and the pedestal jaws being forged to decrease its width and increase its thickness. 30

18. A vehicle truck side frame comprising a single piece of metal cut to shape and having a bolster opening near its center and recesses at its ends, the metal above and below the bolster opening and above the recesses being forged to increase its thickness. 35

19. A vehicle truck side frame comprising a single piece of metal cut to shape and having a bolster opening near its center and recesses near its ends, the metal adjacent said openings and said recesses being forged to increase its thickness, and the edges of the frame and the openings therein being beveled. 40

In testimony whereof, I have hereunto set my hand.

SOREN HANSSON.
